EXCITER LAMP OPERATION

Richard C. Curtis, Short Hills, N. J., and Stephen J. Martin, Long Island City, N. Y., assignors to Faximile, Inc., New York, N. Y., a corporation of Delaware

Application October 21, 1946, Serial No. 704,704

3 Claims. (Cl. 315—279)

1

The present invention concerns electrical lamp operation and, in particular, methods of, and means for operating exciter lamps for sound on film reproduction, facsimile pick-up, and the like from sources of alternating current so that hum or noise due to variations in lamp current are substantially eliminated.

One object of the present invention is to provide circuits for exciter lamp operation which will provide hum-free operation of said lamp from sources of alternating current.

A further object is to provide simple and inexpensive devices for operating exciter lamps from sources of alternating current while eliminating variations in light output over a cycle of the alternating current.

A still further object of the present invention is to provide devices for operating exciter lamps from alternating current sources and for maintaining constant light output not only over a cycle of the alternating current but over long periods of time in the presence of line voltage variations.

These and other objects of the present invention will be apparent from the detailed description of the invention given in connection with the various figures of the drawing.

There are a number of applications in the electronics art for constant light sources. The exciter lamp used in sound film reproduction must give a constant light output particularly over short periods of time as for instance over the cycle of a sixty cycle wave in order that hum and noise may be absent in the reproduction of the sound. Similarly, in facsimile pick-up scanners it is necessary that the light source used in scanning be constant so that hum may not be present in the picture signal. In facsimile it is also necessary that the light be constant over considerable periods of time as well as over the cycle of a sixty cycle wave so that the signal level may remain constant and the average density of the reproduced picture will not be affected by variations in the pick-up scanner light source. In the past it has been necessary to use complicated and expensive methods for operating the exciter lamp in these various devices. One system, which has been used utilizes storage batteries for supplying the lamp and is expensive in the cost and maintenance of the storage batteries and in the charging equipment necessary to keep them in charged condition. Another method which has been used includes expensive rectifiers and filters for converting alternating current from a power line into well regulated constant direct current for the lamp operation. According to the present in-

vention alternating current from a power line is converted into square wave alternating current in which the amplitude of each half cycle is constant but although it reverses polarity, the transition from one polarity to the other takes place so rapidly that the thermal inertia of the lamp prevents its temperature from changing. The lamp temperature, and hence the light output, is not affected by the polarity of the current flowing but only by its absolute value which remains constant with this square wave operation.

In the drawing:

Fig. 1 shows one form of the present invention.

Fig. 2 shows various voltage and current curves useful in explaining the operations of Fig. 1.

In Fig. 1 is shown a source of alternating current 1, connected across a condenser 2, and in series with primary 4, of a transformer 3, in such a way that primary 4, and condenser 2 are in series across the source of alternating current 1. The secondary 5, of transformer 3 is connected across exciter lamp 6. Transformer 3 is so constructed that it will saturate at some desired point and will tend to maintain a constant or substantially constant secondary voltage. The point at which the transformer saturates is controlled by condenser 2, which is chosen to produce saturation at the desired point. The exact characteristics of the transformer and size of condenser 2 will be chosen in any case to suit the requirements of the secondary circuit and degree of squaring of the wave which is desired.

While not intended to limit the invention one set of constants which has been found to be satisfactory in a facsimile exciter lamp system includes the following constants:

Primary of transformer 3, 448 turns of No. 20 wire.

Secondary of transformer 3, 26 turns of No. 18 wire.

Core of transformer 3, standard radio power transformer steel .018" thick.

Length of flux path in transformer 3, 7½".

Stack thickness, 0.8".

45 Cross section of center leg, 1 sq. inch.

Condenser 2, 16 microfarads.

It was found that the circuit as described above gave an exciter lamp in which the light output was considerably more constant than when operated from a sixty cycle alternating current source and was satisfactory for certain applications in a facsimile pick-up scanner. In addition thereto it was found that the output current was constant to within about 0.4% when the primary voltage

varied on the order of 10%. While the actual waveform of the secondary current in any particular case will depend upon the circuit constants, curve B of Fig. 2 shows the waveform obtained with the constants given above. This represents a considerable improvement in attaining hum-free operation over a pure sine wave current operation.

It has been found, furthermore, that if a second transformer 7 is connected with a secondary in series with secondary 5 across lamp 6 and its primary 8 across source 4, that the sine wave current as shown in curve A of Fig. 2 will add to the current as shown in curve B to transformer 3 and condenser 2. This sine wave from transformer 7 will be displaced in phase as shown and will add to the current of curve B in such a way that a more nearly flat or square wave output current will be obtained in lamp 6 as shown at C in Fig. 2. The ratio of transformer 7 between primary and secondary currents is chosen so that its secondary current when added to the secondary current from transformer 3 will produce the most nearly square wave output.

While only one form of the present invention has been shown and described many variations will be apparent to those skilled in the art within the spirit and scope of the invention as set forth in the appended claims:

What is claimed is:

1. A circuit for providing substantially constant light output from a lamp operated from a source of alternating current which includes, in combination, a lamp having substantial thermal inertia, an alternating current transformer having at least a primary and a secondary and capable of considerable current saturation, connections between a source of alternating current and said primary including an electrical capacitor in series to limit the primary current and connections between said secondary and said lamp to provide a flattened current wave to said lamp.

2. A circuit for providing substantially constant light output from a lamp operated from a source of alternating current which includes in

combination, an alternating current transformer including a primary and a secondary, said transformer saturating at a predetermined primary voltage to provide a flattened secondary current, a lamp exhibiting substantial thermal inertia connected to said secondary, and a capacitor connected between said primary and a source of alternating current for limiting current to said primary in the region of said saturation for operating said lamp at a substantially constant temperature.

3. A circuit for providing substantially constant light output from a lamp operated from a source of alternating current which includes, in combination, a first alternating current transformer including a primary and a secondary, said transformer saturating at a predetermined primary voltage to provide a flattened secondary current, a capacitor connected between said primary and a source of alternating current for limiting current to said primary in the region of said saturation, a second alternating current transformer including a primary and secondary, connections between the last said primary and said source of alternating current, a lamp exhibiting substantial thermal inertia, and connections for placing both of said secondaries in series and across said lamp for operating said lamp at a substantially constant temperature.
